INVENTOR

BY Elias Mathews
W. J. Schreiber ATTORNEY

UNITED STATES PATENT OFFICE.

ELIAS MATHEWS, OF DENVER, COLORADO.

DESIGN FOR A DAIRY MILK-CAN.

SPECIFICATION forming part of Design No. 31,933, dated December 5, 1899.

Application filed October 31, 1899. Serial No. 735,431. Term of patent 14 years.

To all whom it may concern:

Be it known that I, ELIAS MATHEWS, a citizen of the United States, residing at Denver, in the county of Arapahoe and State of Colorado, have invented and produced a new and original Design for Dairy Milk-Cans, of which the following is a specification, reference being had to the accompanying drawings, forming a part thereof.

5 Figure 1 is a side elevation of a dairy milk-can, showing my new design. Fig. 2 is a vertical section of the same. Fig. 3 is a top view of the can.

10 As shown in the drawings, the leading or 15 material feature of my design consists of a

milk-can provided with the gradually-sloping wall A, extending from the upper reduced vertical part B to the lower enlarged vertical part E.

Having thus described my invention, what I claim as new, and desire to secure by Letters Patent, is—

The design for a dairy milk-can as herein shown and described.

In testimony whereof I affix my signature in presence of two witnesses.

ELIAS MATHEWS.

Witnesses:

GRACE MYTINGER,
A. J. O'BRIEN.
